(57) **CLAIM**

The ornamental design for a fastener for bicycle, as shown and described.

DESCRIPTION

FIG. 1 is a perspective view of a fastener for bicycle showing my new design, shown in a closed position;

FIG. 2 is a right side elevational view thereof, the left, top and bottom being a mirror image thereof;

FIG. 3 is a front elevational view thereof;

FIG. 4 is a rear elevational view thereof;

FIG. 5 is a perspective view thereof, shown in an open position; and,

FIG. 6 is a right side elevational view of FIG. 5, the left, top and bottom being a mirror image thereof.

The broken lines illustrate unclaimed portions and form no part of the claimed design.
